UNITED STATES PATENT OFFICE.

CHARLES E. HART AND THOMAS CORSCADEN, OF NEW BRITAIN, CONNECTICUT, ASSIGNORS TO THE STANLEY WORKS, OF SAME PLACE.

GAGE FOR PRESS-SLIDES.

SPECIFICATION forming part of Letters Patent No. 425,181, dated April 8, 1890.

Application filed January 3, 1890. Serial No. 335,784. (No model.)

To all whom it may concern:

Be it known that we, CHARLES E. HART and THOMAS CORSCADEN, both citizens of the United States, residing at New Britain, in the 5 county of Hartford and State of Connecticut, have invented certain new and useful Improvements in Gages for Press-Dies, of which the following is a specification.

Our invention relates to improvements in 10 gages for press-dies of the class adapted to gage the edges of the metal, and the objects of our improvement are to accurately center the stock with reference to the die and to hold it firmly while being punched.

15 In the accompanying drawings, Figure 1 is a rear elevation and partial section showing our gage and so much of a press as is necessary to show the connection therewith. Fig. 2 is a side elevation thereof with some of the 20 parts in vertical section. Fig. 3 is a plan view of the lower portion of said parts, the vertically-sliding racks being shown in horizontal section on line $x-x$ of Fig. 1. Fig. 4 is a transverse vertical section thereof, partly 25 in elevation, the plane of section being indicated by the line $y-y$, Fig. 1. Fig. 5 is a rear elevation and partial section of our said improvement, with a modification of the mechanism for operating said gages, and Fig. 6 is 30 a vertical section thereof, partly in elevation, the plane of section being indicated by the line $z-z$ in Fig. 5.

A designates the die-bed, B the dies, C the punch-block, and D the press-slide, all of 35 which, excepting in special features herein-after described, may be of any ordinary construction and adapted for use with any ordinary press.

Our improvement is specially adapted for 40 use in feeding to a die and punch plates or bars of metal of considerable length and width, and will be found especially useful when the cutting-die and punch or dies and punches extend over a considerable portion 45 of the length of the stock. As represented, the stock is passed laterally through the press instead of from front to rear.

Upon the die-bed A and upon each side of the die B we arrange two longitudinal gages 50 7 7, adapted to move to and from each other. In the preferred construction these gages are

provided at each end with an aperture 8, one of which is shown in Fig. 3, the parts above it being broken away for that purpose. We also provide four nuts 9, the same being ar- 55 ranged in pairs of right and left hand threads and provided upon their under side with projections 10, which enter the holes 8 in the gages, as shown in Fig. 2.

In suitable bearings 11, 11, bolted or otherwise firmly secured to the bed A, we arrange the shafts 12 12, each of which is provided with right and left hand threads fitted to the nuts 9, as shown, whereby a rotary motion of the shaft will carry said nuts in each pair to 60 or from each other. At one end of each shaft we secure the pinion 13, which pinions mesh into and are operated by the vertically-sliding racks 14. Said racks are secured in any proper manner to the cross-bar 15, which 65 cross-bar is so connected with the press-slide as to be raised and lowered thereby. This we do by attaching to the press-slide B a socket 16, containing a spring-pressed plunger 17 for forcing said cross-bar downwardly 70 with the press-slide, and lugs 18, provided with adjusting-screws 19, for engaging the under side of said bar to elevate it. For the purpose of preventing the accidental displacement of the screws 19 when adjusted, we pro- 75 vide said screws 19 with the set-nuts 20. The spring 21 within the socket 16 has a tendency to keep the plunger 17 projected from the socket, at the same time permitting it to yield in certain cases, while the head or nut 22 on 80 said plunger at the upper end of the socket prevents the spring from projecting the plunger beyond a certain limit.

A picker or take-off 23 is secured to the die-bed A by means of bolts 24, which pass 85 through hollow blocks 25, which blocks hold the take-off at the proper elevation. The gages 7 7 are slotted laterally at points where the hollow blocks 25 pass through them, so that said blocks do not interfere with the lateral 90 movement of the gages. The racks 14 14 are guided in their vertical movement by means of upwardly-projecting sockets 26, that are formed on or stationarily secured to the die-bed, one of which sockets is shown in vertical 95 section in Fig. 1. In Figs. 5 and 6 we have 100 shown substantially the same gages, but with

a different mechanism for communicating with the downward movement of the cross-bar 15 to the gages 77. The levers 27 are slotted at their outer ends to receive the under edge of the bar 15 and toothed at their inner ends, as shown at 28 in Fig. 6, to engage with and operate companion levers 29. These levers are pivoted on a fixed axis on a projection from the bed and provided on their under side with short arms 30 for entering holes in the ends of the gages 7, whereby a movement of the levers 27 will throw the gages 77 to or from each other. Bearing on the under edge at the outer ends of the levers 27 there are 15 spring-pressed followers 31, which are actuated by springs 32, Fig. 6, within a socket on the bed A, to elevate said levers and cross-bar 15 after each depression and thereby open the gages.

20 The parts are represented in the drawings as they appear when the gages are closed upon the stock. When the press-slide is fully elevated, the nut or head 22 of the plunger 17 will rest upon the upper end of the socket 16 and limit the projection of said plunger. As the press-slide descends, the cross-bar 15 is forced downward by the plunger 17, thereby forcing the gages 77 together, through the connecting mechanism between said cross-bar and gages, until the gages are firmly 25 pressed upon opposite edges of the stock to bring the stock centrally over the die and hold it firmly in advance of any cutting action of the punch. After the gages 77 come to a bearing, so that they can close no farther, the spring 21 permits the cross-bar 15 and plunger 17 to yield, so that the press-slide 30 may complete its stroke while the gages remain stationary. As the press-slide returns, the operating mechanism acts to open the gages 77 slightly, so that the stock may be moved along between the gages to a proper position for being acted upon again, and the

gages are again forced against the stock, and so on repeatedly.

45

We claim as our invention—

1. The combination of a press-slide D, yielding plunger 17, connected thereto, the cross-bar 15, a die-bed, the gages 77, and connecting mechanism between said cross-bar and gages, substantially as described, and for the purpose specified.

2. The combination of a die-bed, the gages 77, arranged to move to and from each other, connecting mechanism for positively moving said gages, a press-slide, and a yielding plunger for acting upon said connecting mechanism, substantially as described, and for the purpose specified.

3. The combination of the gages 77, nuts 9, engaging said gages, the shafts 12, having right and left hand threads within said nuts, the gears 13, and vertically-moving racks 14, operated through the press-slide, substantially as described, and for the purpose specified.

4. The combination of the gages 77, nuts 9, engaging therewith, the shafts 12, having right and left hand threads within said nuts, the gears 13, vertically-moving racks 14, a press-slide, and the yielding plunger operatively connected with said racks for depressing them, substantially as described, and for the purpose specified.

5. The combination of a press-slide, the sockets 16, secured thereto, the spring 21 and plunger 17 within said socket, cross-bar 15, a die-bed, the gages 77, and connecting mechanism between said cross-bar and gages, substantially as described, and for the purpose specified.

CHARLES E. HART.
THOMAS CORSCADEN.
